Primary Examiner — Sandra Snapp

(57) **CLAIM**

The ornamental design for a massage roller ball, as shown and described.

DESCRIPTION

FIG. 1 is a front elevation view of the roller ball massager showing my new design, the back elevation view being a mirror image thereof;

FIG. 2 is a bottom perspective view thereof, showing a magnet within the bottom; and,

FIG. 3 is a bottom perspective view thereof with the magnet removed for ease of illustration.

The new designed proposed by Marcos Cohen was created to attach a magnet at the bottom of the existing “massage roller ball” for hands free application of the device, for example against a refrigerator or a metallic surface attached to a wall.
